UNITED STATES PATENT OFFICE.

CHARLES E. THOMPSON, OF TROY, NEW YORK.

LATHERING UTENSIL.

No. 926,303.

Specification of Letters Patent.

Patented June 29, 1909.

Application filed February 13, 1908. Serial No. 415,782.

To all whom it may concern:

Be it known that I, CHARLES E. THOMPSON, a citizen of the United States, residing at Troy, county of Rensselaer, and State of New York, have invented certain new and useful Improvements in Lathering Utensils, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a bottom plan view of my improved lathering utensil. Fig. 2 is a view in side elevation of the same. Fig. 3 is a central, vertical cross-section of the same taken on the broken line 3—3 in Fig. 1. Fig. 4 is a view in perspective of the handle detached and drawn on a smaller scale than the other figures.

The principal object of my invention is to facilitate the thorough application of the lather to the beard preparatory to shaving.

Other objects of the invention will appear in connection with the following description.

Referring to the drawings, wherein the invention is shown in preferred form, 1, represents a ferrule or head-band of a brush-head, having cemented or otherwise secured therewithin the inner end of a bunch of hair, 2, the inserted end of the bunch of hair being covered and concealed by a cap, 3, secured in position by a retroverted edge flange, 4, on the head-band. The ferrule or head-band is preferably tapered from its inner to its outer end, and the bunch of hair, 2, projects from its inner end in the form of a brush adapted for the laying on of lather preparatory to shaving. By the term hair, as applied to the bunch, 2, I mean to include the various kinds of brush-fiber adapted for use in making shaving brushes. The retroverted edge flange, 4, is part of a peripheral flange, 5, which projects outwardly from the larger end of the head-band.

Mounted upon the brush-head is a body, 6, of soft rubber, having its outer surface convexed and studded with soft rubber projections 7. The body, 6, with its projections constitutes a beard-rubbing body having a roughened or irregular surface adapted for massaging the face and rubbing the lather

previously applied by the brush, 2, well into the beard, and thereby softening the beard preparatory to shaving. I prefer to make the projections, 7, of small area in cross-section, and of such length that they are easily flexible and do not act harshly upon the face or beard. For certain purposes of the invention, the beard-rubbing body may be any body having a yielding, roughened or irregular surface adapted to work the lather into the beard, and to work and render flexible the skin and muscles of the face. The rubber body, 6, is preferably formed with an undercut seat on its inner side at, 8, adapted to receive the flanged end of the brush-head, whereby the body, 6, is detachably secured to the brush-head. The body, 6, being of soft rubber, the flange, 9, surrounding the opening leading to said seat can be forced over the peripheral flange, 5, on the brush-head in applying the body, 6, to, and removing it from, said head.

The utensil is preferably provided with a laterally projecting handle, 10, which may be of any known form, and attached to the brush-head in any known manner. I have shown a preferred form of detachable handle made of a single piece of wire, the respective ends of which are bent to semicircular form, as shown at, 11, adapted to embrace between them the inner end of the head-band, 1, which is provided with a peripheral groove, within which said ends, 11, are adapted to be seated. A hook, 12, is pivoted upon one member of the handle, and adapted to engage the other member thereof to hold the ends, 11, in close engagement with the head-band of the brush-head. The hook, 12, can be disengaged when desired, permitting the members of the handle to be sprung apart sufficiently to release the head-band from their grasp, thus permitting the removal of the handle. The respective members of the handle are formed with outward bends, 13, in a plane at right angles to the axis of the brush-head. The outer end of the handle is formed by the middle of the piece of wire, which is thereat bent to form a reentrant loop, 14, and outward bends, 15, connecting the ends of the loop, 14, and outward bends, 15, connecting the ends of the loop, 14, with the intermediate portion of the handle. The bends, 15, are in a plane oblique to the plane of the bends, 13, and the reentrant loop, 14, is in a plane at right angles to the plane of the bend, 15. The enlargements

thus formed by the bend, 13, and by the bend, 15, and reentrant loop, 14, afford a convenient grasp for the hand in using the utensil.

- 5 In using my improved utensil, the soap is worked into a lather and laid upon the face and beard by the brush, 2, in the usual manner, after which the beard and face are rubbed with the studded body, 6, until the 10 lather is well worked into the beard, and the beard and face become soft and suitable for shaving. Additional lather can be laid upon the face from time to time by means of the brush, 2.
- 15 The manner in which the brush-head is mounted in the handle permits the head to be rotated upon the handle, if desired, to facilitate the distribution of the lather.
- What I claim as new and desire to secure by 20 Letters Patent is—
1. A lathering utensil comprising in combination a brush-head; a body of hair projecting from said brush-head; a beard-rubbing body of rubber having a roughened surface 25 mounted upon said brush-head; and a handle projecting laterally from said brush-head.
  2. A lathering utensil comprising in com-

bination, a brush-head; a body of hair projecting from one end of said brush-head; a 30 beard-rubbing body having a surface studded with flexible projections mounted upon the opposite end of said brush-head; and a laterally projecting handle.

3. A lathering utensil comprising in combination a brush-head; a body of hair projecting from one end of said brush-head; a beard-rubbing body of soft rubber having a 35 convexed surface studded with flexible projections mounted upon the opposite end of 40 said brush-head; and a laterally projecting handle.

4. In a lathering utensil, the combination with a brush-head having a peripheral flange; of a body of hair projecting from 45 said brush-head; and a beard-rubbing body of soft rubber having a roughened surface and provided with an undercut seat adapted to detachably receive the peripherally flanged portion of the brush-head.

In testimony whereof, I have hereunto set my hand this 12th day of Feb. 1908.

CHARLES E. THOMPSON.
